UNITED STATES PATENT OFFICE.

CHARLES G. REVENY, OF SAN FRANCISCO, CALIFORNIA.

BOLTING-UP DEVICE.

1,371,396.

Specification of Letters Patent. Patented Mar. 15, 1921.

Application filed March 15, 1920. Serial No. 366,053.

To all whom it may concern:

Be it known that I, CHARLES G. REVENY, a citizen of the United States, residing in the city and county of San Francisco and State of California, have invented a new and useful Improvement in Bolting-Up Devices, of which the following is a specification.

My invention relates to improvements in bolting-up devices wherein a bolt is temporarily secured to retain contact of two or more plates or elements to be bolted or riveted together.

This invention is an improvement on my device disclosed in my copending application filed the 24th day of February, 1920, Serial No. 361,352, reference to which application is hereby made.

The main object of the present invention 20 is to provide means for reducing the cost of the bolting up device hereinabove referred to wherein a bolt having a latch is inserted through the plates or members to be secured and is operated by a single operator from one side of the work or structure only, both in applying as well as in removing the bolts after the riveting process is completed.

In my copending application a cam plate 30 is used to engage and retain one end of the bolt and to exert sufficient pressure upon the members to be secured to retain contact of said members during the riveting process.

In the present invention the cam plate 35 or impinging cam is only used for the initial process of drawing the plates together and for holding the bolt while a cheaper form of temporary securing means is inserted.

It is also an object of the present invention to provide a cheaper form of bolt having a maximum efficiency.

I accomplish these several objects by means of the device disclosed in the drawings forming a part of the present specification wherein like characters of reference are used to designate similar parts throughout the said specification and drawings, and in which—

Figure 1 is a side elevation of my improved bolt, partly in section, and showing the latch in a registering position;

Fig. 2 is a similar view disclosing the latch in a laterally projecting or securing 55 position;

Fig. 3 is a side elevation of my improved

device as applied to two plates or members to be connected, the position of the cam in the impinging position being disclosed in dotted lines;

Fig. 4 is a horizontal sectional view of Fig. 3 showing the cam in the impinging position disclosed in dotted lines in Fig. 3 of the drawings; and

Fig. 5 is a front elevation of the impinging cam.

Referring to the drawings my improved bolt consists of an ordinary unthreaded bolt 1 having the head 2 thereof provided with oppositely positioned arcuate portions 3, the purpose of which will hereinafter be more fully described.

The bolt 1 is provided nearly throughout the length thereof with a longitudinally disposed slot 4 within which is slidably and 75 rotatably mounted a latch 6 by means of laterally extending lugs 7 mounted on said latch 6 and extending into a shorter longitudinally disposed slot 8 within the bolt 1 and at right angles to the slot 4 therein, the 80 position of said slot 8 being such that when the latch is laterally extending from the slot 4 and impinging against the outer end thereof, the lugs 7 will be in spaced relation 85 relatively to the ends of the slots 8 thereby preventing exposure of the lugs 7 to a shearing strain when the latch 6 is impinged against the end of the slot 4, as disclosed in Fig. 3 of the drawings.

The latch 6 is provided with an extension 9 on one end thereof to engage a recess 11 adjacent one end of the slot 4 to retain registration of the latch 6 with the bolt 1 while in one position whereby said bolt 1 and latch 6 may be readily inserted 95 into aligned or registered apertures or holes 14 and 15 in members 16 and 17 to be riveted or otherwise permanently secured together.

A bifurcated arcuate cam 18 is arranged 100 to straddle the bolt 1 the outer surfaces or peripheries being arranged to impinge against one of the elements or members to be connected and the inner surfaces of said bifurcated cam 18 being arranged to engage the arcuate surfaces or portions 3 of the bolt head 2 as disclosed in Fig. 3 of the drawings.

Rotation of the cam 18 about the axis or center of the arcuate portions 3 of the 110 bolt's head 2 will cause said inner surfaces of said bifurcated cam 18 to move the bolt

1 longitudinally and thereby impinge the latch 6 against the opposite side of the members 16 and 17 and move or clamp said members tightly together.

5 When the members 16 and 17 are moved tightly together a wedge 19 is placed within the end of the slot 4 of said bolt 1 adjacent the head end of said bolt and impinged tightly and securely between the end of the 10 slot 4 and the nearest member to be secured.

The bifurcated cam 18 is then released from the bolt head 2 and applied to the next bolt to be secured.

In this manner the cam 18 is used as a tool 15 instead of being left as a securing means. As the wedges 19 are cheaper and more easily handled than the bifurcated cam it is obvious that a great reduction in expense as well as a great lessening in the weight to 20 be transported where a number of bolts are to be used, is obtained by the provision of the wedge 19, in place of the cam 18, as a temporary securing means.

Washers 20 may be placed between the 25 wedge 19 and plate 17 to build up and fill the space between the adjacent face of the member 17 and the wedge 19 thereby facilitating the use of short wedges, the only displacement of the wedge being required 30 under this arrangement, being slightly greater than the thickness of one washer 20.

By means of this improvement one operator may readily bolt up plates where only one side is accessible to said operator, 35 as the bolt with its registered latch 6 may be easily inserted from the operator's side of the work. After insertion a partial or substantially half rotation of the bolt will 40 permit the action of gravity to extend the latch laterally from the sides of the bolt and thereby provide an obstruction on the opposite side of the work from the operator whereby said bolt may be prevented from 45 being extracted when the securing means are positioned and operated on the opposite end thereof.

In removing the bolts it is only necessary to again partially rotate the same until the latch 6 falls into registration with the bolt 1, 50 as disclosed in Fig. 1 of the drawings, when the said bolt 1 may be easily withdrawn.

It is obvious from the foregoing that I have provided an improved means for temporarily securing together plates and other

members to be finally permanently riveted 55 or otherwise connected, said means being adaptable to insertion and operation from one side of the work only and easily and readily manipulated by a sole operator.

Having thus described my invention what 60 I claim as new and desire to secure by Letters Patent is—

1. A bolting-up device comprising a longitudinally slotted bolt; a latch movably mounted within one end of said slot and 65 adapted to register with the bolt when in one position and to extend laterally from said bolt when the same is in another position; means for engaging the end of the bolt opposite the latch and for 70 moving members to be clamped against said latch when extended; and a wedge arranged to engage the end of the slot opposite the latch and to move and temporarily retain said members against said latch. 75

2. A bolting up device comprising a longitudinally slotted bolt having arcuate portions formed on the inner side of the head of said bolt; a latch movably mounted within one end of said slot and arranged to register therewith when the bolt is in one position and to be extended laterally from said bolt when in another position; means for engaging the arcuate portions of the bolt head for moving members to be clamped 85 against the latch when extended; and means for engaging the end of the slot opposite the latch and said members to retain said members against said latch. 80

3. A bolting up device comprising a longitudinally slotted bolt having arcuate portions formed on the inner side of the head of said bolt; a latch movably mounted within one end of said slot and arranged to register therewith when the bolt is in one position and to be extended laterally from said bolt when in another position; means for engaging the arcuate portions of the bolt head for moving members to be clamped 95 against the latch when extended; and a wedge adapted to be inserted within the end of the slot opposite the latch and to engage and retain said members against said latch. 100

In witness whereof I hereunto set my signature.

CHARLES G. REVENY.
